SPARK PLUG

Emil Kohout and Kenneth Lee Ingersoll, Jackson,
Mich.

Application April 27, 1940, Serial No. 332,078

8 Claims. (Cl. 123—169)

This invention relates to spark plugs, one of the objects being to provide an effective sectional spark plug which can be produced at low cost and which utilizes interchangeable electrodes.

A further object is to provide a spark plug which can be seated within the motor head where it will be maintained at a low temperature during the operation of the motor.

A still further object is to provide a spark plug which dispenses with the casing commonly used and eliminates compression leakage usually occurring between the engine head and the spark plug casing.

A still further object is to provide a spark plug the interchangeable portions of which can be assembled readily while out of position in the motor, adjusted relative to each other and then assembled in proper relation within the motor head.

Another object is to produce a spark plug which, while utilizing interchangeable electrodes, can nevertheless be produced generally at a cost less than that of the usual spark plug.

A further object is to provide a spark plug the parts of which are so assembled that none of them can fall into the combustion chamber under any circumstances.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a central vertical section through the spark plug and that portion of a motor head in which it is seated.

Figure 2 is a section on line 2—2, Figure 1.

Figure 3 is a plan view of one of the compression washers.

Figure 4 is an end elevation of that end of the porcelain core with which the washer is to be assembled.

Figure 5 is a central vertical section through the electrode ring.

Figure 6 is a section through a portion of a modified form of spark plug.

Referring to the figures by characters of reference, A designates a portion of a motor head provided with a recess 1 the outer end of which

has its wall screw-threaded as shown at 2 while its inner end has an opening 3 adapted to communicate with the combustion chamber of the motor. An annular shoulder 4 is formed in the recess about opening 3 and another annular shoulder 5, which is inclined, is formed by the wall of the recess at a point between the ends thereof.

Shoulder 4 forms a seat for a ring 6 in which 10 are anchored grounded electrodes 7. In the structure illustrated two of these electrodes are provided, these being oppositely disposed and having terminals extended toward each other. It is to be understood, however, that any desired number of electrodes can be used and that the electrodes can be of any shape preferred. They are so assembled with the ring that they can be inserted readily into the opening 3 while ring 6 is being placed on its seat 4. The ring, when inserted downwardly, contacts with the wall of recess 1.

The core of the spark plug has been indicated at 8 and can be formed of porcelain or any other suitable insulating material. The core includes 25 a body portion 9 the diameter of which is somewhat less than the internal diameter of recess 1. From one end of this body projects a tapered extension 10 centrally disposed, and that end of the body 9 from which the projecting portion 10 extends is tapered to provide an annular shoulder 11. One or more fins 12 are extended from this shoulder and along the extension 10 and, when the parts of the spark plug are properly assembled, these fins will bear against ring 6 and hold it to its seat 4, as shown in Figure 1.

The outer end of the body portion 9 of core 8 is formed with an inclined annular shoulder 13 which surrounds the base of an elongated tapered stem 14 forming a part of the core and 30 which stem, at its outer end, is enlarged annularly as at 15 to provide a shoulder 16.

A central longitudinal bore 17 is extended 45 within stem 14 from its outer end and terminates within the body portion 9 of the core. The inner end of this bore provides a tapered seat 18 located about one end of an opening 19 which extends through body 9 and its extension 10 at the center thereof.

A compression gasket, indicated at 20 and 50 which is substantially conical, is adapted to be mounted on the shoulder 11 and this gasket has a central opening 21 for the reception of the extension 10 and one or more recesses in the wall 55 of the opening as at 22, for the reception of the

fin or fins 12. Another compression gasket or washer 23 is adapted to fit on the shoulder 18 and around the base of stem 14 and is located where it can be engaged and compressed by a gland nut 24 which is extended into recess 1 and is in engagement with the threaded portion 2.

A tubular stud 25 is mounted on the outer end 15 of stem 14 and is provided with an enlarged base 26 from which depends an annular flange 27. This flange is adapted to fit snugly about the enlarged portion 15 and after being assembled therewith, is adapted to be crimped under the shoulder 16 so as thus to hold the stud assembled with stem 14. A screw cap 28 detachably engages stud 25 and in this cap at the center thereof is a small recess 29 for receiving the tapered end 30 of the central electrode 31. This central electrode is extended downwardly within the bore 17 and opening 19 and is formed with a tapered enlargement 32 adapted to bear against the seat 18 as shown in Figure 1. A firm contact between the parts can be made by tightening the cap 28 on the stud 25 and when electrode 31 is thus assembled, it will have its active end extended between the points of the grounded electrode 7 as shown.

The ring 6 which carries the grounded electrodes 7 is provided with notches 33 corresponding with the recesses 22 and the fins 12 and when this ring is in position its notches are so located as to receive the fins. Furthermore the upper end of the ring is flared, as at 34 so as to constitute an extension of the shoulder 5 on which the gasket 20 can rest.

In assembling this spark plug the washer 23 is placed about stem 14 and said stem is then inserted through nut 24. Thereafter stud 25 is attached to the enlarged end 15 of the stem as already explained and electrode 31 is inserted into the core where it is held firmly against seat 18 by tightening the cap 28. Core 8 can then be inverted and washer 20 and ring 6 placed thereon with the fins extending through recesses 22 and into the notches 33. Electrodes 7 can then be adjusted relative to the electrode 31 after which the ring and gasket can be removed from the core. The ring is then dropped into the recess 1 until it rests on the shoulder or seat 4. Gasket 20 is fitted about the core and said core is then inserted in the recess 1 and brought into position to allow the fins 12 to drop into the notches 33. Thereafter the gland nut 24 is tightened within the recess and this results in holding the parts of the spark plug together securely and also properly assembled with the motor head. An air space is formed between the body 9 and the wall of the recess as shown in Figure 1 at 35 and as the wall of the recess is cooled by the water surrounding it within the motor head, it will be obvious that the spark plug can be maintained at a low temperature while the motor is functioning.

As this spark plug is not provided with the usual casing, there is no danger of a leakage taking place between the casing and the motor head. Furthermore as the spark plug is seated within the motor head, it can be kept cool as already explained. Whenever it is desired to change any of the electrodes, the change can be effected readily as will be obvious.

The central electrode 31 can be of any shape desired and also of any proportions found useful.

Should it be desired to use this spark plug in lieu of the ordinary type, the ring 6 and other parts could be seated within an exteriorly threaded casing 35 as shown in Figure 6, this casing 75

taking the place of the walls of the recess shown in Figure 1 and providing the shoulder 36 for the compression washer 20 and also the threads 37 for engagement by the nut 24.

What is claimed is:

1. In a spark plug the combination with a member having a recess and superposed annular shoulders therein, of a ring removably seated on one of the shoulders, an electrode projecting therefrom and beyond the recess, there being a notch in the ring, a washer seated on the other shoulder, an insulating core, means on the core and insertible into the washer and the notched ring for holding said washer and ring against relative rotation, a central electrode carried by and projecting from the core, and means engaging a wall of the recess for compressing the washer between its supporting shoulder and the core.

2. In a spark plug the combination with a member having a recess open at its ends and provided with superposed interior shoulders constituting seats, of a ring detachably seated on one of the shoulders and having a notch in one face, an electrode extending from the ring and through one open end of the recess, a compression washer mounted on the other shoulder, an insulating core insertible into the recess and onto the washer, means carried by the core and insertible into the washer and into the notch in the ring for holding said ring and washer against relative rotation, said ring providing a seat for the washer, and means adjustably engaging the wall of the recess for compressing the washer between the core and its shoulder and the ring.

3. In a spark plug the combination with a member having a recess open at its ends and provided with superposed interior shoulders constituting seats, of a ring detachably seated on one of the shoulders and recessed in one face, an electrode extending from the ring and through one open end of the recess, a compression washer mounted on the other shoulder, an insulating core insertible into the recess and onto the washer, means carried by the core for compressing said washer against the ring and shoulder for holding said ring and washer against relative rotation, said ring providing a seat for the washer, and means adjustably engaging the wall of the recess for compressing the washer between the core and its shoulder and the ring, said means including a gland nut and a compression washer interposed between the nut and the core.

4. In a spark plug the combination with a member having a recess open at its end and superposed annular shoulders within the recess, of a ring removably seated on one of the shoulders, said ring having a notch in one face, an electrode extending from the opposite face of the ring and through one open end of the recess, an insulating core insertible into the recess and having an annular shoulder, a compression washer interposed between the shoulder on the core and one of the shoulders in the recess, means carried by the core and seated within the washer and the notch in the ring for holding the washer and ring against relative rotation, means engaging the wall of the recess for holding the core against movement within the recess, and an electrode seated within and extending from one end of the core.

5. In a spark plug the combination with a member having a recess open at its end and superposed annular shoulders within the recess, of a ring removably seated on one of the shoulders,

said ring having a notch in one face, an electrode extending from the opposite face of the ring and through one open end of the recess, an insulating core insertible into the recess and having an annular shoulder, a compression washer interposed between the shoulder on the core and one of the shoulders in the recess, means carried by the core and seated within the washer and the notch in the ring for holding the washer and ring against relative rotation, means engaging the wall of the recess for holding the core against movement within the recess, an electrode within the core, cooperating means on the core and electrode for limiting the movement of the electrode in one direction, a threaded tubular stud secured to the core, and a screw cap engaging the stud, said cap constituting a thrust bearing for the electrode in the core.

6. The combination with a motor head having a recess extending therethrough, the walls of the recess being water-cooled and said recess having superposed interior annular shoulders, of a ring removably mounted on one of the shoulders and having a notch in one face, an electrode extending from the other face of the ring and through one end of the recess, a compression washer on the other shoulder in the recess, an insulating core bearing against the washer, means on the core insertible into the washer and the notch in the ring for holding the washer and ring against relative rotation, said ring providing a seat for a portion of the washer, an electrode seated within the core and projecting therefrom adjacent to the first named electrode, and means for detachably securing the core and its electrode 35 against relative movement.

7. The combination with a water-cooled motor head having a recess extending therethrough provided with spaced interior annular shoulders, of a ring detachably seated on one of the shoulders and having a notched face, a grounded electrode extending from the opposite face of the ring and through one end of the recess, a compression washer supported on the other shoulder and on the ring, an insulating core insertible into the recess and into the washer and ring, means on the core and seated in the washer and ring for holding them against relative rotation, and an electrode carried by and extending from the core.
- 15 8. The combination with a water-cooled motor head having a recess extending therethrough provided with spaced interior annular shoulders, of a ring detachably seated on one of the shoulders and having a notched face, a grounded electrode 20 extending from the opposite face of the ring and through one end of the recess, a compression washer supported on the other shoulder and on the ring, an insulating core insertible into the recess and into the washer and ring, means on the core and seated in the washer and ring for holding them against relative rotation, an electrode 25 removably seated within and projecting from one end of the core, a threaded stud connected to the core at one end, and a screw cap engaging the stud and constituting a thrust bearing for the electrode in the core.
